US0D1104126S

(12) **United States Design Patent** (10) **Patent No.:** **US D1,104,126 S**
(45) **Date of Patent:** **** Dec. 2, 2025**

(54) **SAFETY GOGGLES**

(71) Applicant: **Criticore, Inc.**, Charlotte, NC (US)
(72) Inventors: **Jessica Gregory**, Charlotte, NC (US);
Thomas Gregory Winn, Charlotte, NC (US)
(73) Assignee: **CRITICORE, INC.**, Charlotte, NC (US)

(**) Term: **15 Years**

(21) Appl. No.: **29/921,555**

(22) Filed: **Dec. 18, 2023**

(51) **LOC (15) Cl.** **16-06**
(52) **U.S. Cl.**
USPC **D16/312**

(57) **CLAIM**

The ornamental design for “safety goggles” as shown and described.

DESCRIPTION

FIG. 1 is a left front perspective view of the “safety goggles” of Applicant’s invention.

FIG. 2 is a right back perspective view of the “safety goggles” of Applicant’s invention.

FIG. 3 is a left side elevation view of the “safety goggles” of Applicant’s invention.

FIG. 4 is a right side elevation view of the “safety goggles” of Applicant’s invention.

FIG. 5 is a front elevation view of the “safety goggles” of Applicant’s invention.

FIG. 6 is a back elevation view of the “safety goggles” of Applicant’s invention.

FIG. 7 is a top view of the “safety goggles” of Applicant’s invention; and,

FIG. 8 is a bottom view of the “safety goggles” of Applicant’s invention.

1 Claim, 8 Drawing Sheets
